SHEET FEEDING AND MARKING METHOD AND MACHINE.

Application filed September 25, 1923. Serial No. 664,775.

The present invention relates to methods of and machines for feeding and delivering such articles as sheets of paper, and its chief object is to provide an improved method and machine for marking or separating the sheets so delivered into bundles or reams, each containing a predetermined number of the sheets. Other objects will appear hereinafter, and will be pointed out in the claims.

10 The invention will be fully explained in connection with the accompanying drawings, in which Fig. 1 is a diagrammatic view, partly in side elevation and partly in longitudinal section, of a paper-sheet-cutting machine of well known construction, with the present invention attached thereto; Fig. 2 is a rear view of a stack of sheets as delivered into the lay-boy shown in Fig. 1, marked in accordance with the present invention; Fig. 3 is a side elevation of a portion of the operating mechanism of the tag-feeding devices, the view being enlarged with respect to Figs. 1 and 2, and the parts being shown in the relative positions occupied by them when the tag-feeding devices are ineffective; Fig. 4 is a similar view, with the parts in relative positions such as to render the tag-feeding devices effective to feed the tag; Figs. 3^a and 4^a are similar views, showing further steps in the operation; Fig. 5 is a section, upon the same scale, of a portion of the said operating mechanism, the section being taken generally upon the line 5—5 of Fig. 3, looking in the direction of the arrows; Fig. 6 is a plan of a preferred, intermittently operating tag-feeding device and associated parts, shown enlarged with respect to Fig. 1; Fig. 7 is a side elevation of the structure shown in Fig. 6; Fig. 8 is a diagrammatic view of a preferred mechanism for rendering the tag-feeding device effective; Fig. 9 is a front elevation of a portion of the mechanism shown in Figs. 6 and 7; and Fig. 10 is a section taken upon the line 10—10 of Fig. 5, looking in the direction of the arrows.

45 The machine of the present invention is, for illustrative purposes, shown applied to a paper-sheet-cutting-and-feeding machine of well known type, such as is commonly employed in paper mills to sever the rolls 2 of paper, Fig. 1, that are produced in the paper-making machines, into individual sheets, and to feed and stack the severed sheets into lay-boys 4. Any desired, con-

venient number of rolls 2 of paper may be operated upon simultaneously in the same machine. Three such rolls are illustrated diagrammatically in Fig. 1. The webs 3 of paper from the rolls 2 are led together to feed rolls 6, by which the paper is advanced to disk cutters 8, which sever the paper into longitudinal strips of the desired width. The severed strips are then advanced by feed rolls 10 and 12 to rotary cutters 14 and 16 by which the strips are severed into sheets of the desired length. Tapes 18 and 20 then feed the sheets into the lay-boys 4, which are automatically lowered from time to time to maintain approximately uniform the level of the sheets that are stacked therein.

50 The sheets so stacked in the lay-boys 4 are separated into bundles, each containing a predetermined number of the sheets. It is customary to separate them into reams of 480 or 500 sheets. According to present practice, this separation is effected during the sheet-stacking process in the lay-boys by girls or other operatives who stand in front of the lay-boys, at 22, Fig. 1, and mentally count the sheets, one by one, as they are delivered. The girls place a paper tag between two adjacent sheets at the completion of each count. These tags are inserted from the front of the stack, at 22. The completed stack is thus supposed to be separated by these tags into reams or bundles of any desired number of sheets. The accuracy of the count, however, depends upon an inherently inaccurate or undependable mental counting process. Automatic counting and marking devices of various kinds have accordingly been proposed at various times in the past, but for one reason or another, —whether too complicated, or cumbersome, or unreliable in practice (however operative in theory), or unsuited to the needs of the particular machine,—they have not proved to be satisfactory, so that the girls are still universally employed, and it is still impossible to tell, in advance, how many sheets a mentally-counted ream really contains.

55 According to the present invention, the sheets are counted automatically, as they are delivered into the lay-boy 4, by an accurate machine that is not dependent upon a failing, human, counting memory; and thin, paper tags 24, Figs. 1 and 2, are automatically inserted between adjacent, predeter-

- mined sheets at the completion of each count; so that the reams or bundles thus counted and marked contain just the desired number of sheets, and neither more nor less.
- 5 Not only are accuracy and efficiency thus attained, but the cost is considerably reduced, since the girls are no longer needed, and may be employed to better advantage elsewhere.
- 10 Feed rolls 26 and 27, Figs. 6 and 7, automatically advance intermittently, through a guide 28, and between a movable knife 30 and a stationary knife 32, Fig. 9, a paper strip 34 that is unwound from a reel 36.
- 15 The end 38 of the paper strip, is thus intermittently advanced, at the proper time, and becomes inserted between adjacent sheets 104 and 106, Fig. 1, of the stack and, after it is severed by the knives 30 and 32, constitutes a tag 24. The feed roll 26 is mounted upon an end of a bell-crank lever 40, intermediately pivoted at 41, and the other end of which is spring pressed at 42 to cause the feed roll 26 to maintain the paper strip tightly in engagement with the feed roll 27. The feed rolls 26 and 27 are provided with meshing gears, as shown. To advance the strip 34, therefore, it is necessary to rotate intermittently the feed roll 26 only, the feed roll 27 being positively driven by its gear from the feed roll 26, and the two rolls positively pulling the strip 34 through between them.
- The feed rolls 26 and 27 are situated at the rear end of the guide 28, at a point just to the rear of and just below the upper sheets of the stack of sheets in the lay-boy, and the knife 32 is situated at the other end. A shaft 44, situated to the rear of the guide 28, is provided with a gear 126, keyed thereto at 220, which drives the feed rolls 26 and 27 through a train of gearing 128. The train of gearing 128 makes it possible to position the feed rolls 26 and 27 properly, at a distance from their driving shaft 44. By feeding the strip at a point so close to the stack, there is no tendency for the strip to buckle or sag in the guide 28. This obviates danger of the strip getting stuck in the guide, which would prevent the strip from being advanced at all. A lever 31, pivoted at 33, by its own weight presses the strip 34 against a seat 35 in the bell-crank lever, just to the rear of the feed rolls 26 and 27, the better to guide the strip. The shaft 44 is intermittently rotated by a continuously rotating pawl 46, Figs. 3, 4, 3^a, 4^a and 5, when the latter engages the walls of a recess 48 provided upon a normally stationary collar member 50 that is fixed to the shaft 44. The recess 48 is thus, in effect, provided upon the shaft 44. The pawl 46 is pivotally mounted at 52 upon a collar 54 that is keyed at 55 to a gear wheel 56. The gear wheel 56, with the collar 54 that is keyed thereto, is loosely mounted upon the shaft 44. The gear wheel 56 is driven by a gear wheel 58, Fig. 8, from a gear wheel 60 that is mounted upon a shaft 62. Gear wheels 59 are interposed, as a convenient medium of properly determining the direction and speed of rotation of the gear wheel 56. The shaft 62 may be driven from the shaft of the rotary cutter 16 in any well known manner, as, for instance, in the manner illustrated in a copending application, Serial No. 563,274 filed May 24, 1922, of which the present application is a continuation in part. The rotation of the shaft 62 is therefore a measure of the number of sheets that are cut by the knife 16 and delivered into the lay-boy. The collar 54, that carries the pawl 46, is thus continuously rotated loosely in a circular path about the shaft 44, from the shaft of the cutter 16, or in any desired manner, so long as the pawl 46 does not engage the walls of the recess 48. When the pawl 46 does engage the walls of the recess 48, however, it will actuate the recess-carrying collar 50; and the shaft 44, to which the recess-carrying collar 50 is secured, will obviously rotate also, causing the feed rolls 26 and 27 to feed the end 38 of the strip 34 between two adjacent sheets 104 and 106 of the stack, as is illustrated in Fig. 1. The feeding of the strip 34 is therefore controlled by the continuously rotating pawl 46. Rotation of the shaft 44 in the wrong direction is prevented by one or more pawls 69 operating, with graduated effect, upon one or more ratchet wheels 71 (one only is illustrated in Fig. 10).
- The pawl 46 is normally prevented from entering the recess 48 by a gate 70, Figs. 3, 4, 3^a, 4^a and 5, that is provided upon a collar 72 that is loosely mounted upon the reduced end 74 of the shaft 44. In the position normally occupied by the collar 72 upon the shaft 44, the gate 70 overlies or covers the forward wall 49 of the recess 48, as shown in Fig. 3, in the path of the pawl 46. So long as the gate 70 overlies this forward wall 49 of the recess 48, the continuously rotating pawl 46 can not engage this wall 49, but rides idly over the gate. Upon the gate becoming displaced from the position of Fig. 3 to that of Fig. 4, the pawl 46, during its next journey around the shaft 44, will be pressed into the recess 48 by a spring 76. The pawl 46, continuing its rotation, will now carry the recess-containing collar 50 with it, and the latter, being secured to the shaft 44, will cause the feed rolls 26 and 27 to advance the end 38 of the strip 34, as above described. Upon reaching the wall 78, Fig. 4, of the gate 70, the pawl 46 will ride out of the recess 48, as shown in Fig. 3^a, whereupon the shaft 44

will cease rotating, and the strip 34 will be no longer advanced. The forward wall 49 of the recess 48 will thus be left behind the gate 70, in the dotted-line position of Fig.

5 3^a. The pawl 46 will then again continuously rotate idly, as before. It should be noted that when the pawl 46 leaves the forward wall 49 of the recess 48 behind the gate 70, as just described, the shaft 44 has 10 not quite completed a revolution, for the recess 48 occupied originally the position shown in full lines in Fig. 4, whereas it now occupies the position shown in Fig. 3^a. The revolution of the shaft 44 is completed later, 15 as will shortly be described, to effect the actuation of the movable knife 30.

It will now be necessary to explain how the gate 70 is actuated from the position of Fig. 3 to that of Fig. 4 to uncover the recess 48, and thus permit the pawl 46 to actuate the feed rolls 26 and 27 by engaging the forward wall 49 of the recess 48. The gate 70 is provided with a pin 80 that projects into an elongated opening 82, Fig. 8, provided at one end of a lever 84. The lever 84 is intermediately pivoted at 86, and its other end 88 rides along a cam track 90 of a cam disk 89 that is rigidly secured to a counting disk (not illustrated) so as to 30 rotate therewith. The cam disk 89 is shown mounted upon a shaft 189. As is explained in the above-named application, each revolution of the shaft of the cutter 16 may effect an angular movement of the cam disk 89 35 corresponding to any convenient desired number of sheets, but further description of this feature will be omitted as not necessary to an understanding of the present invention. The cam track 90 is provided with 40 a recess 94 having a sharp abrupt shoulder 96, a gradually inclined shoulder 98 and an intermediately disposed wall 100. The counting disk (not shown) and the cam disk 89 are rotated, step by step, as is described 45 fully in the said application, in the direction of the arrow, Fig. 8, as a unit, and the cam disk 89 will be regarded in the present application as typifying a counter. When the sharp abrupt shoulder 96 reaches the end 88 50 of the lever 84, a spring 102 will move the lever 84 to cause the end 88 of the lever to engage the wall 100 of the recess 94. The other end of the lever 84 will thus be moved downward, as viewed in Fig. 8, causing the pin 80 to be moved downward also. The 55 collar 72 will therefore be rocked from the position of Fig. 3 to that of Fig. 4, causing the gate 70 to uncover the recess 48. The pawl 46 will then be enabled to cause actuation of the feed rolls 26 and 27, as above described. The downward movement of the lever 84 is, of course, timed to take place at the end of a cycle of operation of the counter, say, after a ream has been delivered 60 and counted. It is not essential that the

marker be operated once to every revolution of the cam disk 89, for cam disks 89 having a plurality of recesses 94 may be employed, the location of the recess 94, in each case, controlling the operation of the marker. 70

It has been pointed out above that the pawl 46 will leave the recess 48 at a time when the latter is in the position of Fig. 3^a, and before the shaft 44 has made a complete revolution. This nearly complete revolution 75

of the shaft 44 is effected in about half the time required to make one delivery into the lay-boy. During this nearly complete revolution of the shaft 44, the end 38 of the strip 34 has been rapidly fed from the rear 80

of the stack, in a direction at a substantial angle to the horizontal direction of feed of the sheets, shown nearly vertical in Fig. 7, 85

into the path of feed of the next following sheet, which constitutes the first sheet 106 90

of the next ream. If the end 38 of the strip were fed horizontally forward, or at an angle not sufficiently far from the horizontal, being constituted of thin paper, it might 95

strike the rear of the stack of sheets, and not enter between adjacent sheets at all, thus falling to the floor and failing to mark the separating line between the reams. If fed 100

at an angle so near to the horizontal, furthermore, the tags, if it is succeeded in getting them inserted between the sheets, are frequently carried by the sheet 106 so far 105

in between the sheet 104 and the sheet 106 that it is lost to view, and its function as a marker becomes lost. It is therefore de- 110

sirable to feed the end 38 of the strip 34 at a substantial enough angle to the direction of feed, so as to avoid having the strip engage the rear of the stack or to become lost 115

between sheets of the stack. If fed at such angle into the path of feed of the sheet 106, the head of the sheet 106 will be sure to strike it and lay it down flat upon the last sheet 104 of the ream just completed; which 120

is readily effected by the thin, flexible character of the strip 34. All possibility of the end 38 of the strip 34 becoming displaced is thus avoided. It is furthermore unnecessary to time accurately the moment when 125

the end of the strip is fed upward, as would be the case if it were fed horizontally, or nearly so, which timing it is necessary to adjust for sheets of different length. In order to insure feeding the strip at such angle, an intermediate portion of the guide 120

28 is curved, as shown, so as to rise nearly vertically, as illustrated in Fig. 7 at 29. The end 38 of the sheet is fed upward for a distance sufficiently great so as to make sure that it will rise above the top sheets of the stack and into the path of travel of the sheet 106. 130

When the end 38 has thus been laid flat by the sheet 106 upon the sheet 104, it is still too early to sever it from the strip 34,

as the severing process might pull it out of place. It is preferable to wait until a number of sheets have been fed forward over the sheet 106; their combined weight then serving to hold the end 38 of the strip 34 in place while it is severed. The number of sheets that shall so be fed forward for this purpose depends upon the length of the wall 100 of the recess 94. The cam disk 89 continuing to rotate, as the counter continues to count the additional sheets so fed forward, the end 88 of the lever 84 will ultimately leave the wall 100 and ride up on the inclined shoulder 98 of the recess 94. The other end of the lever 84 will then be returned upward to its normal position, shown in Fig. 8, carrying the pin 80 upward with it. This will have the effect of returning the gate 70 from the position of Figs. 4 and 3^a to that of Figs. 3 and 4^a, uncovering the forward wall 49 of the recess 48, which at this time occupies the dotted-line position of Fig. 3^a, as explained above. During the next cycle of rotation of the pawl 46 about the shaft 44, therefore, it will engage the forward wall 49 of the recess 48, and thus actuate the recess-carrying disk 50 from the position of Figs. 3^a and 4^a to the position of Fig. 3. Upon the recess 48 being thus returned to the position of Fig. 3, the gate 70, occupying now the position shown in Figs. 3 and 4^a, will again cause the pawl 46 to leave the recess 48, and the pawl 46 will again continue to rotate idly, as before. This completes the revolution of the collar 50 and, therefore, of the shaft 44 to which it is secured. Upon the completion of this revolution, the knife 30 will actuate to sever the end 38 from the strip 34, the severed end constituting one of the tags 24. The lever 84 is thus adapted to occupy two positions successively, in one of which it controls the feed roll 26 to insert the end 38 of the strip 34 between adjacent sheets of the stack, and in the other of which it causes the knife 30 to sever the end 38 of the strip, these two positions being controlled by the cam disk 89. The mechanism for operating the knife 30 will now be described.

The knife 30 is adapted to be reciprocated in a vertical plane in guides 108, to cooperate with the stationary knife 32, by a lever 110, one end of which is pivoted at 114 and to the other end of which the knife is connected at 112. An intermediate portion 116 of the lever 110 is adapted to be engaged by a rotary cam 118. When the recess 48 is moved by the pawl 46 from the position of Figs. 3^a and 4^a to the position of Fig. 3, the lever 110 is actuated by the cam 118, in opposition to the force exerted by a spring 120 to move the knife 30 upward, as seen in Figs. 7 and 9, causing the end 38 to become severed from the strip 34. It will be noted, from Figs. 6 and 9, that the knives 30 and 32 are inclined to each other in two planes, so as to provide a very effective, shearing cut. The roll cam 118 is mounted upon a shaft 123 having a gear 124 among the same train of gearing 128 that drives the feed rolls 26 and 27 from the shaft 44. The knife is thus operated in timed relation to the operation of the feed rolls 26 and 27 by the shaft 44, which first operates through nearly a complete revolution to cause the feed rolls 70 to feed the strip 34, and then remains stationary until the desired number of sheets have been fed over the sheet 106, and which finally operates through the remainder of its revolution to cause the roll cam 118 to engage the lever 110, thereby causing the knife to sever the end 38 from the strip 34. The knife is returned to normal position before the shaft 44 comes to rest. The cam roll 118 is adjustable to adjust the time of operation of the knife 30. A partition 134 separates the train of gearing from the guide 28 to prevent the paper strip 34 binding between the gears and clogging the machine.

Upon the retreat of the movable knife 30, the new end 38 of the strip 34 is left under the stationary knife 32. Owing to the substantially vertical direction of feeding movement of the end 38 of the strip, there would be a tendency for the strip to strike against the knife 32, and prevent further advance of the end of the strip, at the next feed movement of the feed rolls 26 and 27. To prevent this happening, a lever 37 is adapted to pivot, by its own weight, about a pivotal point 39, so as to enter between the two knives 30 and 32, as is illustrated in Fig. 7 thereby engaging the end 38 of the strip and pushing it forward, beyond and between the knives. The next forward feed movement of the feed rolls 26 and 27 will therefore result in advancing the end 38 of the strip in a nearly vertical direction, as before described, and as illustrated more particularly in Fig. 7, to one side of the cutter 32. The lever 37 is forced out of the way of the movable knife 30, at each upward movement of the same, in any desired manner, as by means of a cam 141 upon the inner face of the knife 30 that is adapted to engage the lever 37 when the knife is moved upward, and that is adapted to become disengaged from the lever 37 on the downward movement of the knife. The use of the said cam 141 is, in practice, found to be unnecessary, as the knife 30 may force the lever 37 out of the way by direct engagement with its projecting upper portion. If the lever 37 is constituted of soft metal like lead, it will not dull or otherwise injure the knife. The return gravity movement of the lever is limited by an integral projection 53 that is adapted to engage the rear of the knife 32.

According to the present invention, then,

the end 38 of the strip is automatically advanced into position in a direction nearly at right angles to the direction of feed of the sheets so that it may be struck by the 5 first sheet 106 of each new ream and laid flat thereby between adjacent sheets 104 and 106 of adjacent reams, and it is then severed from the strip 34, the tag 24 being thus left in place to mark the boundary between the 10 two reams. It has been explained that the successive operations of the feeding and severing mechanisms for the strip 34 are controlled by the end 88 of the lever 84, through the recess 94 in the cam disk 89 that 15 is secured to rotate with a counting disk (not shown). The operation of the counter will not be described herein because unnecessary to an understanding of the present invention, and because any counter, operating 20 in any well known manner, may equally well be employed without departing from the spirit and scope of the present invention.

It will be clear from the above description that any desired number of feed rolls 25 26 and 27 and associated mechanisms may all be controlled by the same shaft 44. Three lay-boys 4 are illustrated in the above-named application, each provided with a 30 separate marking attachment adapted to supply tags 24. As the feed rolls 26 and 27 of the three markers are controlled by the same shaft 44, a single counter suffices for all three lay-boys. As many lay-boys as are 35 attached to the machine may each be provided with a marker.

The markers, as is explained above, are controlled by the counter. Ordinarily, it is desired to count and mark reams either of 40 500 sheets or of 480 sheets. Using the duplex type of paper-cutting-and-feeding machine shown diagrammatically in Fig. 1, it is possible to employ two counters, one controlled by the cutter 16, as above described, and the other controlled by the cutter 14. 45 The two counters may be mounted at opposite sides of the machine. The operation of the counter that is controlled by the cutter 16 has already been described. The other counter may be driven from the cutter 14. 50 As has been explained above, the lever 84 controls, through the pawl 46, the operation of the shaft 44, this shaft, in turn, controlling the feed wheels 26 and 27. A similar lever (not shown, but illustrated in the 55 above-referred-to application), operated by the said other counter, may control, through a similar pawl, the operation of a shaft 122. To operate the marker from the shaft 122, the key 220, Fig. 7, is removed, so as to 60 render the gear 126 loose upon the shaft 44, and a gear 224, that is loose when the gear 126 is keyed to the shaft 44, is keyed at 222 to the shaft 122, instead. Rotation of the shaft 122, through an idler gear 125, will 65 thus drive the feed rolls 26 and 27 through

the same train of gearing 128, the gear 126 now rotating idly on the shaft 44. The idler gear 125 enables the gears 124 and 126 to drive the feed rolls 26 and 27 in the same direction. The feed rolls 26 and 27 are thus 70 operated to feed the strip 34 in the same manner as before described, except that they are now operated from the shaft 122 instead of from the shaft 44; and the knife-controlling-cam wheel 118 still operates to control 75 the knife, as before described.

It will be understood that the invention is not limited to the exact embodiment that is, herein illustrated and described, and is subject to modification and change by persons 80 skilled in the art. All such modifications and changes are considered to be within the spirit of the invention, and the scope of the invention is defined by the appended claims.

What is claimed is:

1. The method of feeding sheet material that comprises feeding a sheet, and interposing a strip in the direction of feed of the sheet at a substantial angle to the direction of feed, whereby the head of the sheet will 85 strike the strip and deflect it.

2. The method of feeding and stacking sheet material and marking the stacked sheets that comprises feeding a plurality of sheets, and interposing a tag in the path of feed of one of the sheets at a substantial angle to the direction of feed, whereby the head of the said one sheet will strike the tag and deflect it towards a prior-fed sheet.

3. The method of feeding and stacking sheet material and marking the stacked sheets that comprises feeding a plurality of sheets in a substantially horizontal direction into a lay-boy, and feeding a tag in a substantially vertical direction into the path of feed of one of the sheets whereby the head of the said one sheet will strike the tag and lay it against a prior-fed sheet.

4. The method of feeding and stacking sheet material and marking the stacked sheets that comprises feeding a plurality of sheets in a substantially horizontal direction into a lay-boy, and interposing a tag in the path of feed of one of the sheets from a position just to the rear of and just below the upper sheets of the stack at a substantial angle to the direction of feed so as to avoid striking the stack, whereby the head of the said one sheet will strike the tag and lay it against a prior-fed sheet.

5. The method of feeding and stacking sheet material and marking the stacked sheets that comprises feeding a plurality of sheets into a lay-boy, feeding the end of a flexible strip into the path of feed of one of the sheets at a substantial angle to the direction of feed of the sheet, whereby the head of the sheet will strike the end of the strip and lay it against a prior-fed sheet, and severing the end of the strip.

6. The method of feeding and stacking sheet material and marking the stacked sheets that comprises feeding a plurality of sheets in a substantially horizontal direction into a 5 lay-boy, feeding the end of a flexible strip into the path of feed of one of the sheets from a position just to the rear and just below the upper sheets of the stack in a substantially vertical direction so as to avoid 10 striking the stack, whereby the head of the said one sheet will strike the end of the strip and lay it against a prior-fed sheet, continuing to feed sheets into the lay-boy, and severing the end of the strip upon a pre- 15 determined number of additional sheets having been fed into the lay-boy.
7. A machine of the class described having, in combination, means for feeding a sheet, and means for interposing a strip in 20 the direction of feed of the sheet at a substantial angle to the direction of feed, whereby the head of the sheet will strike the strip and deflect it.
8. A machine of the class described having, in combination, means for feeding a 25 plurality of sheets, and means for interposing a tag in the path of feed of one of the sheets at a substantial angle to the direction of feed, whereby the head of the said one sheet will strike the tag and deflect it towards a prior-fed sheet.
9. A machine of the class described having, in combination, a lay-boy, means for feeding sheets into the lay-boy, and means 30 for feeding a tag into the path of feed of one of the sheets at a substantial angle to the direction of feed of the sheets, whereby the tag is adapted to be struck by the said one sheet as it is fed into the lay-boy 35 and laid by the said one sheet upon a prior-fed sheet.
10. A machine of the class described having, in combination, a lay-boy, means for feeding sheets in a substantially horizontal direction into the lay-boy, and means for 40 feeding a tag in a substantially vertical direction into the path of feed of one of the sheets, whereby the head of the said one sheet will strike the tag and lay it against a prior-fed sheet.
11. A machine of the class described hav- 45 ing, in combination, a lay-boy, means for feeding sheets into the lay-boy, and means for feeding the end of a flexible strip into the path of feed of one of the sheets at a substantial angle to the direction of feed of the sheets, whereby the end of the strip is adapted to be struck by the said one sheet as it is fed into the lay-boy and laid by the said one sheet upon a prior-fed sheet, and means for severing the end of the strip. 55
12. A machine of the class described having, in combination, a lay-boy, means for feeding sheets in a substantially horizontal direction into the lay-boy, and means for interposing a tag in the path of feed of one of the sheets from a position just to the rear of and just below the upper sheets of the stack at a substantial angle to the direction of feed so as to avoid striking the stack, whereby the 60 head of the said one sheet will strike the tag and lay it against a prior-fed sheet. 70
13. A machine of the class described having, in combination, a lay-boy, means for feeding a plurality of sheets in a substantially horizontal direction into the lay-boy, means for feeding the end of a flexible strip into the path of feed of one of the sheets from a position just to the rear and just below the upper sheets of the stack in a substantially vertical direction so as to avoid 75 striking the stack, whereby the head of the said one sheet will strike the end of the strip and lay it against a prior-fed sheet, and means for severing the end of the strip upon the feeding of an additional predetermined number of sheets into the lay-boy. 80
14. A machine of the class described having, in combination, means for feeding a plurality of sheets, means for interposing the end of a strip in the path of feed of one of the sheets at a substantial angle to the direction of feed, whereby the head of the said one sheet will strike the tag and deflect it towards a prior-fed sheet, and means timed 85 to operate with the feeding means for severing the end of the strip. 90
- In testimony whereof, I have hereunto subscribed my name this 7th day of September, 1923.

CHARLES B. MAXSON.
